HIGHWAY CROSSING GATE

John C. Lindner, Rochester, N. Y., assignor to
General Railway Signal Company, Rochester,
N. Y.

Application December 24, 1938, Serial No. 247,587

11 Claims. (Cl. 39—7)

This invention relates to crossing gates for blocking highway traffic on a highway intersecting a railroad, and more particularly to a crossing gate operated wholly electrically.

In the electrical operation of crossing gates by reason of the length of such gates certain problems are encountered that have not been encountered in the electrical operation of semaphore blades for railway signalling purposes.

One of the obstacles surrounding the economic operation of crossing gates is due to the enormous wind resistance offered by gates of a length to extend across a highway, by reason of which wind resistance the operation of the gate may be either aided or retarded depending on the direction of the wind. If the electrical operation of the gate is retarded this effect may be compensated for by installing a higher gear ratio gear train or by employing a larger motor. If, on the other hand, the direction of the wind is such as to aid the motor in moving the gate arm it is found necessary to add supplemental means for preventing excessive speed of operation of the gate arm. The second obstacle encountered when operating a crossing gate wholly electrically is the variable and greatly increased forces that are encountered when ice and sleet accumulates on the gate or the gate arm is broken off, as for instance by an automobile driving through the gate. This increased force when the gate is broken off is due to the fact that the force exerted by the counterweight of the gate is in a direction to move the gate to its clear position and is considerably in excess of the biasing force that existed in the opposite direction before the gate was broken off. In other words, the crossing gate by reason of its length is of considerable weight and in practice a counterweight of considerable weight is added so that the biasing force of the gate tending to move it to its stop position is almost entirely counter-balanced. If now the crossing gate is broken off, either due to excessive loading as by ice or sleet, or by being struck by an automobile, the counterweight alone remains, as a result of which the mechanism will be operated toward its clear position at a tremendous speed.

In accordance with the present invention it is proposed to employ a highway crossing gate which is provided with a counterweight to almost neutralize the torque produced by the gate and to provide a motor and suitable gearing for operating the gate to its clear vertical position, and to provide normally energized hold-clear mechanism for electrically holding the gate in its clear

position, which hold-clear mechanism is released when the clearing potential is removed, to provide a friction slip clutch through the medium of which the hold-clear mechanism may retard the operation of the mechanism near the end of its clearing stroke and hold the gate against movement thereafter, and to provide electro-dynamic braking means to retard the operation of the crossing gate in its gravitational movement from the clear to the stop position, and to provide suitable pole changer contacts operated only when the gate arm is broken off and when operated is effective to afford a snubbing circuit to electro-dynamically brake the motor when the counterweight is moving from the stop to the clear position.

Other objects, purposes and characteristic features of the present invention will be pointed out in the following specification and will in part be obvious from the accompanying drawing showing a highway which crosses a railroad track and which highway is provided with electrically operated crossing gates embodying the present invention, the mechanical and electrical apparatus of only one of these crossing gates being shown.

Gate operating structure

Referring to the drawing the railroad track illustrated is divided by insulating joints 1 into track circuits, each track circuit of which energizes one of the coils of the interlocking relay R. This interlocking relay R is preferably of the construction shown in either the patent to Field No. 1,824,131 or in the patent to Henry et al. No. 1,969,075. This interlocking relay R through front contacts 2 and 3 included in series controls the slow acting repeater relay RR. Each of the crossing gates O and P conventionally shown adjacent the highway comprises a gate plate P, having fastened thereto a gate arm 10 and a counterweight 11. In practice this counterweight is so located and of such weight that the counterweight 11 will greatly aid in moving the gate 10 to its clear position, but also of such weight that upon release of all extraneous forces the gate will gravitate to its horizontal stop position. To the gate is secured, as by bolts, a conducting link 8 of brittle metal, such as lead, zinc or cast iron, which link 8 is connected in series with the pole-changer relay PC and is also included in series with the energizing circuit for the repeater relay RR. Breaking of the gate arm will invariably break the link 8 and will result in deenergization of the relays PC and RR. This link 8 may, if desired, extend the entire length 55

of the gate 10. This gate plate P is fastened to a main shaft 12, driven by the series motor M through the medium of gears 13, 14, 15, 16 and 17. This series motor M includes a series field 5 winding F and an armature A. To the motor shaft 20 are keyed, but freely slideable, clutch plates 21, of which only one has been illustrated, which clutch plates are pressed toward each other through the medium of a coil spring 22 10 and between these clutch plates 21 and freely rotatable on the shaft 20 is a clutch wheel 23. It is thus seen that this clutch wheel 23 is frictionally held from freely rotating on the shaft 20 by reason of the clutch plates 21 frictionally engaging 15 opposite sides of this clutch wheel 23 due to the action of the coil spring 22.

Under normal operating conditions, that is, when the gate is in its clear position and the hold-clear mechanism HC is energized, the clutch 20 wheel 23 which tends to rotate counterclockwise is locked in its then position by a locking pawl 25. This locking pawl 25 is slidably supported in one of the links of a toggle mechanism through the medium of three pins 26, 27 and 28 passing 25 through the plates 29 and 30 of this link of the toggle mechanism, this locking pawl being biased into an engaging position by a spring 31. These plates 29 and 30 are pivoted as by a pin 32 to a stationary lug 33. The lower end of these plates 30 are pivoted, as by a pin 34 passing through the vertical arm 36 of the angle lever 35-36, this angle lever 35-36 being pivoted to stationary lugs through the medium of a pin 37.

This toggle mechanism is normally held in its 35 effective holding position by an electro-magnet including high resistance coils H and low resistance coils L. Upon deenergization of the magnet HC the weight of the armature 42 in addition to the force exerted on the pawl 25 will 40 cause the pawl 25 to release. This electro-magnet includes the usual back yoke 40, cores 41 and armature 42. This electro-magnet when deenergized causes the angle lever 35-36 to assume an abnormal position, where the stop pin 43 45 engages a stop plate 44, such that the locking pawl 25 no longer engages between the lugs on the clutch wheel 23. This electro-magnet is so constructed that if the high resistance coils H and the low resistance coils L are connected in series 50 and energized by the source of direct current illustrated by the legends (+) and (-), there will be insufficient flux to operate the hold-clear mechanism HC to its locking position. If, however, only the low resistance coils L are connected 55 across this source of current the armature 42 will be operated to its attracted position, thereby operating the locking pawl 25 to a position to lock the clutch wheel 23. This electro-magnet will, however, maintain its armature 42 in its 60 attracted condition, if once lifted to this position, by the flux emitted when the high resistance coils H and the low resistance coils L are connected in series across this source of current.

The shaft 45 illustrated by a dashed line is 65 provided with three pairs of contacts 46-47, 48-49 and 50-51. This shaft 45 is driven in accordance with the rotation of the shaft 12 through the medium of gear sectors 52 and 53. In order to provide electro-dynamic snubbing 70 through the medium of the motor M when the crossing gate 10 gravitates to its horizontal stop position a snubbing relay SR has also been provided. This snubbing relay has a high resistance winding h and a low resistance winding l.

75 For operation of the mechanism from the clear

position to the stop position the residual magnetism in the field poles of the series motor M is of a magnetic polarity to induce a current in the armature which by flowing through the field winding will increase the magnetic strength 5 of the field poles. This is particularly true because the armature A rotates in a reverse direction than when energized from the battery, so that the voltage generated in the armature is in a direction to create a series field current which 10 flows in a direction to strengthen the residual magnetic field which produced such current. This flow of current will of course produce electro-dynamic braking of motor M. This current flows through the back contact 88 of the snubbing relay SR and through snubbing resistance 87. If now it is desired to produce electro-dynamic snubbing action when the gate arm 10 breaks, and the mechanism is operated from its stop to its clear position by gravity through the medium 20 of the counterweight 11, it is necessary to reverse either the field winding or the armature in the series motor M. In applicant's construction this desired result has been accomplished by including pole-changer contacts 56 and 57 in 25 the series motor circuit which if operated to reverse position cause the armature to be reversed in this circuit, and these pole changer contacts are operated by the pole-changer relay PC, which relay PC is deenergized only when 30 the link 8 is open circuited because the gate arm 10 has been broken.

Operation of system

Referring to the drawing, let us assume that 35 there is a train approaching the highway and that as a result of this train one of the coils of the interlocking relay R is deenergized thereby opening the circuit for the repeater relay RR and resulting in the dropping of its contact 86. 40 The opening of this contact 86 deenergizes the circuit including the high resistance coils H and the low resistance coils L of the hold-clear magnet in series. Deenergization of the magnet causes the armature 42 to drop thereby causing the 45 locking pawl 25 to be moved to the left out of engagement with the slip clutch wheel 23. By reason of the weight of the crossing gate 10 over that of its counterweight 11, this crossing gate will gravitate toward the horizontal position and 50 in so doing will rotate the armature A of the motor M in the opposite direction from that in which the motor was last electrically operated. By reason of the residual magnetism remaining in the motor field a voltage will be built up in 55 the armature A which will create a current in the snubbing circuit in a direction to flow in the field winding F in a direction to aid this residual magnetism, so that a comparatively strong magnetic field will be set up in the stator 60 poles of the motor M. This strong magnetic field will of course set up a larger current through the snubbing circuit extending from the (-) or ground connection, through the snubbing resistance 87, through the back contact 88 of the 65 snubbing relay SR, through the field winding F of the motor M, through the pole-changer contact 56, through the armature A of the motor M, through pole changer contact 51, to the other ground or (-) connection, thereby causing a 70 reaction between the armature A and the field F of the motor M tending to retard the rotation of the armature A, and thereby retarding the speed of operation of the crossing gate 10 toward its horizontal stop position. If the prevailing 75

wind should be in a direction to aid the return of the gate additional dynamic braking current will flow due to the slight increase in the motor speed thereby causing additional braking.

5 Let us now assume that the approaching train has passed the crossing and that the repeater relay RR is again energized. Energization of the repeater relay RR causes closing of its contact 86 thereby closing a circuit through the series motor M, which may be traced from the terminal (+) of a suitable source of direct current, front contact 86 of the relay RR, contacts 46-47 of the operating mechanism, low resistance winding 1 of the snubbing relay SR, the field F of the motor M, the pole-changer contact 56, the armature A and the pole changer contact 57, to the other terminal (-) of that source of current. The completion of this circuit will cause sufficient current to flow through the low resistance winding 1 of the snubbing relay SR to cause this snubbing relay SR to pick up and open its back contact 88. With the back contact 88 of relay SR opened a useful multiple path for the motor M is established which includes the high resistance winding h of the relay SR, and the snubbing resistance 87. This multiple branch circuit including the high resistance winding h of the relay SR assures that the contact 88 will remain open in spite of sparking at the brushes and intermittent opening of the circuit of this motor M. As the motor M operates it turns the gear sector 53 in a clockwise direction and when it has operated through an angle of 85 degrees the contacts 48-49 are closed and when it has reached the 87 degree position the contacts 50-51 are closed. Closure of the contacts 48-49 completes a circuit from the terminal (+), through contacts 86 of relay RR, contacts 46-47 and contacts 48-49 of the operating mechanism, 40 through the low resistance winding L of the hold-clear magnet, as a result of which this hold-clear magnet is energized to an extent to pick up its armature 42. After three additional degrees of operation of the crossing gate 18, 45 namely, when it has been operated to the 88 degree position from its horizontal position, the contacts 46-47 of the operating mechanism open, thereby removing the shunt which had been established around the high resistance coils 50 H of the hold-clear magnet by the contacts 46-47, 48-49 and 50-51 in series, as a result of which the high resistance coils H and the low resistance coils L of this hold-clear magnet are connected in series through a circuit including front contact 86 of the relay RR and contacts 50-51 of the operating mechanism in series. This circuit by reason of the high resistance of the coils H draws very little current but at the same time is able to maintain the armature 42 in its raised position. When the armature 42 of the hold-clear mechanism was actuated to its attracted position the locking pawl 25 of course engaged the friction wheel 23 of the friction slip clutch as a result of which a braking action is applied to the motor M. The slipping between the friction wheel 23 and the clutch plates 21 will soon bring the motor M to a stop.

In order to prevent the crossing gate from being operated and held beyond the 91 degree position the contacts 50-51 have been made so short as to be closed only between the 87 degree and the 91 degree position. It thus follows that if the gate is operated beyond the 91 degree position the hold-clear magnet will be deenergized 75 by the opening of the contacts 50-51. If the

gate now settles back below the 91 degree position and the contacts 50-51 reclose the circuit for the hold-clear magnet its armature 42 will not be picked up, because it is incapable of being picked up by a circuit including the high resistance coils H and the low resistance coils L in series. The gate will thus be returned a little further and when it reaches the 88 degree position and the contacts 46-47 of the operating mechanism reclose, the circuits reenergizing the 10 motor M and for shunting the high resistance coils H of the hold-clear magnet are closed so that this hold-clear magnet will be picked up through its low resistance coils L.

Let us now assume that the crossing gate is 15 assuming its stop position and that an automobile strikes the gate and breaks off the arm 18 at just about the time that the train passes beyond the crossing and picks up the repeater relay RR. When this occurs the circuit for the 20 motor M heretofore traced is not completed because breaking of the gate arm 18 and its check or conducting link 8 causes dropping of the relay RR, so that the motor circuit is not completed. This breaking of the check link 8 also 25 causes dropping of the pole-changer relay PC. With the relay PC deenergized a snubbing or dynamic braking circuit is closed which includes the armature connections reversed, that is, a snubbing circuit that will function for operation 30 of the motor in the gate clearing direction. In other words, if the crossing gate was assuming the stop position when the gate arm was broken off, as has been assumed, then the gravitational force of the counterweight 11, which is no longer 35 counter-balanced by the gate, will act tending to assume the clear position very quickly, which would have broken the mechanism upon reaching the end of the stroke were it not for the special snubbing circuit that was completed by dropping of the pole-changer relay PC. This special 40 snubbing circuit includes the armature and the field of the motor M so connected in series that the voltage generated in the armature A when rotating in the clearing direction produces a current in the field winding to increase the field 45 strength and the voltage generated so that each increases the other to cause a large dynamic braking current to flow in the snubbing circuit including the snubbing resistance 87. 50

The applicant has thus shown and described an electrically operated crossing gate embodying certain new features including novel electrodynamic braking means for retarding the speed of the operating mechanism for any reason as, 55 for instance, due to the breaking of the crossing gate, which would result in a tremendous torque being exerted upon the mechanism due to the force of the counterweight which normally counter-balances the gate itself. Although a rather 60 specific construction of applicant's invention has been illustrated in the drawing it is desired to be understood that this has been done to facilitate description of the invention rather than to illustrate its scope or the particular construction 65 preferably employed in practicing the invention, and it is further desired to be understood that such changes as are within the scope of the appending claims may be made without departing from the spirit or scope of the present invention. 70

What I claim as new is:

1. In an electrically operated crossing gate, the combination with a crossing gate pivoted to a stationary support and partially counterbalanced 75

- so as to be biased toward the horizontal stop position only to an extent to move to and return its operating mechanism to such stop position, an electric motor and reduction gearing for operating said gate to a substantially vertical clear position, a shaft for said motor, a friction slip clutch on said shaft, a hold-clear mechanism effective to engage said clutch to render it effective when said motor is energized and said gate is 5 in its clear position, a check link on said gate electrically broken when said gate is broken off, and a snubbing circuit effective to brake said motor when running in a clearing direction effective only if said check link is broken.
- 15 2. In an electrically operated crossing gate, the combination with a crossing gate pivoted to a stationary support and partially counterbalanced so as to be biased toward the horizontal stop position only to an extent to move to and 20 return its operating mechanism to such stop position, a series motor and reduction gearing for operating said gate to a substantially vertical clear position, a shaft for said motor, a friction slip clutch on said shaft, a hold-clear mechanism 25 effective to engage said clutch to render it effective when said motor is energized and said gate is in its clear position, a snubbing circuit closed when said motor is disconnected from the source of current and effective to electro-dynamically 30 brake said motor when it is turned in a direction opposite to the direction in which it is operated to move said gate to its clear position, a check link on said gate electrically broken when said gate is broken off, and means for reversing the 35 armature with respect to its field of said motor in said snubbing circuit when said check link is broken, whereby said motor is dynamically braked for operation of said operating mechanism toward its clear position.
- 40 3. In an electric motor operated crossing gate, the combination with a gate fastened to a horizontal shaft and partly counterbalanced by a counterweight so that the shaft is biased to a horizontal stop position but is very strongly biased to a clear position if the gate is broken off, 45 a gear train, a series motor for operating said shaft to a clear position through the medium of said gear train, a snubbing circuit including in series said motor and a snubbing resistance for 50 electro-dynamically braking said motor when operated in a direction to rotate said shaft from a clear position to a stop position, and means for reversing the armature with respect to the field of said series motor when said gate is broken off, 55 whereby said snubbing circuit functions for operation of said motor from the stop position to the clear position.
4. In an electric motor operated crossing gate, the combination with a gate fastened to a horizontal shaft and partly counterbalanced by a counterweight so that the shaft is biased to a horizontal stop position but is very strongly biased to a clear position if the gate is broken off, 60 a gear train, a series motor for operating said shaft to a clear position through the medium of said gear train, a clutch wheel frictionally connected to the shaft of said series motor; a hold-clear magnet having a high resistance coil and a low resistance coil and which if in an active condition locks said clutch wheel; a control relay; 65 a first contact, a second contact and a third contact controlled by said shaft of which the first contact opens when said shaft assumes a predetermined position and of which the second contact and third contact close when said shaft has 70
- 75

almost reached said predetermined position; an operating circuit for said motor including a contact of said control relay, a source of current and said first contact; a circuit for said low resistance coil including in series said source, a contact of 5 said control relay said first contact and said second contact in series; a circuit for said high resistance coil and said low resistance coil in series including a contact of said control relay, said source and said third contact; a snubbing 10 circuit for said motor including in series said motor and a snubbing resistance; and means for reversing the armature with respect to the field of said series motor and for deenergizing said control relay when the gate is broken off. 15

5. In an electric motor operated crossing gate, the combination with a gate fastened to a horizontal shaft and partly counterbalanced by a counterweight so that the shaft is biased to a horizontal stop position but is very strongly biased to a clear position if the gate is broken off, 20 a gear train, a series motor for operating said shaft to a clear position through the medium of said gear train, a clutch wheel frictionally connected to the shaft of said series motor; a hold-clear magnet having a high resistance coil and a low resistance coil and which if in an active condition locks said clutch wheel; a control relay; 25 a snubbing relay, a first contact, a second contact and a third contact controlled by said shaft of which the first contact opens when said shaft assumes a predetermined position and of which the second contact and third contact close when said shaft has almost reached said predetermined position; a pole-changer relay; an operating circuit 30 for said motor including a contact of said control relay, a source of current, contacts of said pole-changer relay, a winding of said snubbing relay and said first contact; a circuit for said low resistance coil including in series said source, a contact of said control relay, said first contact and said second contact in series; a circuit for 35 said high resistance coil and said low resistance coil in series including a contact of said control relay, said source and said third contact; a first snubbing circuit for said motor including in series said motor, contacts of said pole-changer relay closed when said pole-changer relay is energized, 40 a back contact of said snubbing relay and a snubbing resistance; and a second snubbing circuit including the same elements as said first snubbing circuit but with the contacts of said pole-changer relay reversed so that the armature of said series motor is reversed with respect 45 to the field winding of such series motor. 50

6. In an electric motor operated crossing gate, the combination with a gate fastened to a horizontal shaft and partly counterbalanced by a counterweight so that the shaft is biased to a horizontal stop position but is very strongly biased to a clear position if the gate is broken off, 55 a gear train, a series motor for operating said shaft to a clear position through the medium of said gear train, a clutch wheel frictionally connected to the shaft of said series motor; a hold-clear magnet having a high resistance coil and a low resistance coil and which if in an active condition locks said clutch wheel; a control relay; 60 a snubbing relay, a first contact, a second contact and a third contact controlled by said shaft of which the first contact opens when said shaft assumes a predetermined position and of which the second contact and third contact close when said shaft has almost reached said predetermined position; a pole-changer relay; an operating circuit 65

70

75

cuit for said motor including a contact of said control relay, a source of current, contacts of said pole-changer relay, a winding of said snubbing relay and said first contact; a circuit for 5 said low resistance coil including in series said source, a contact of said control relay, said first contact and said second contact in series; a circuit for said high resistance coil and said low resistance coil in series including a contact of said 10 control relay, said source and said third contact; a first snubbing circuit for said motor including in series said motor, contacts of said pole-changer relay closed when said pole-changer relay is energized, a back contact of said snubbing relay 15 and a snubbing resistance; a second snubbing circuit including the same elements as said first snubbing circuit but with the contacts of said pole-changer relay reversed so that the armature of said series motor is reversed with respect to 20 the field winding of such series motor; and means for deenergizing said control relay and said pole-changer relay simultaneously.

7. In an electrically operated crossing gate, the 25 combination with a gate arm pivotally supported through the medium of a horizontal shaft to which this gate arm is secured, a gear train, a series motor for operating said gate arm through the medium of said gear train, a counterweight for almost entirely counterbalancing said gate 30 arm allowing however sufficient bias so that said gate arm by gravitational forces acting thereon may operate said motor and gear train to the stop position from the clear position, a control relay, a pole changer relay, a control circuit for operating said gate arm to the clear 35 position including a source of current and contacts of said control relay and said pole changer relay closed when said relays are in their energized condition, a first snubbing circuit including contacts of said pole changer relay closed when such pole changer relay is in its energizing condition and a snubbing resistance, and a second snubbing circuit including contacts of 40 said pole changer relay closed only when said pole changer relay is deenergized and including said snubbing resistance.

8. In an electrically operated crossing gate, the combination with a gate arm pivotally supported through the medium of a horizontal shaft 50 to which this gate arm is secured, a gear train, a series motor for operating said gate arm through the medium of said gear train, a counterweight for almost entirely counterbalancing said gate arm allowing however sufficient bias 55 so that said gate arm by gravitational forces acting thereon may operate said motor and gear train to stop position from the clear position, a

control relay, a pole changer relay, a control circuit for operating said gate arm to the clear position including a source of current and contacts of said control relay and said pole changer relay closed when said relays are in their energized condition, a first snubbing circuit including contacts of said pole changer relay closed when such pole changer relay is in its energizing condition and a snubbing resistance, a second snubbing circuit including contacts of said 10 snubbing circuit closed only when said pole changer relay is deenergized and including said snubbing resistance, and means for deenergizing said pole changer relay when said gate arm is broken off. 15

9. In a power operated crossing gate, in combination, power operated means, a movable gate positionable horizontally or vertically, means only partly counterbalancing the gate so the gate is biased to the horizontal position only to an extent to move to, and return its operating mechanism to, the horizontal position, a check link on the gate and made effective only when the gate is broken, and brake means controlled by the check link, and effective, only when the 20 check link is effective, to brake the power operated means when it is moving in a direction to move the gate to its vertical position. 25

10. In a power operated crossing gate, in combination, electric power operated means, a piv- 30 oted gate positionable horizontally or vertically, means only partly counterbalancing the gate so the gate is biased to the horizontal position only to an extent to move to, and return its operating mechanism to, the horizontal position, 35 a check link on the gate and made effective only when the gate is broken, and dynamic brake means controlled by the check link and effective, only when the check link is effective, to brake the power operated means when it is moving in 40 a direction to move the gate to its vertical position.

11. In a power operated crossing gate, in combination, electric power operated means, a piv- 45 oted gate positionable horizontally or vertically, means only partly counterbalancing the gate so the gate is biased to the horizontal position only to an extent to move to, and return its operating mechanism to, the horizontal position, a check link on the gate and made effective only when the gate is broken, and dynamic brake means controlled by the check link and effective, only when the check link is effective, to brake the power operated means only when it is moving in 50 a direction to move the gate to its vertical 55 position.

JOHN C. LINDNER.
